CLAIM

The ornamental design for a cutting tool with sleeve, as shown and described.

DESCRIPTION

FIG. 1 is a front elevation view of a cutting tool with sleeve showing my new design, the rear view being a mirror image; FIG. 2 is a side elevation view thereof, the opposite side being a mirror image;

FIG. 3 is a top plan view thereof;

FIG. 4 is a bottom plan view thereof;

FIG. 5 is a perspective view of the cutting tool shown separately for clarity of illustration;

FIG. 6 is a front elevation view of FIG. 5;

FIG. 7 is a rear elevation view of FIG. 5;

FIG. 8 is a top plan view of FIG. 5;

FIG. 9 is a bottom plan view of FIG. 5;

FIG. 10 is a side elevation view FIG. 5;

FIG. 11 is an opposite side view of FIG. 5;

FIG. 12 is a front elevation view of the sleeve shown separately for clarity of illustration, the rear view being a mirror image;

FIG. 13 is a side elevation view of FIG. 12, the opposite side being a mirror image;

FIG. 14 is a top plan view of FIG. 12; and,

FIG. 15 is a bottom plan view of FIG. 12.
